UNITED STATES PATENT OFFICE.

JOACHIM TORRES-GARCIA, OF NEW YORK, N. Y.

TRAVELING TOY.

1,427,657.

Specification of Letters Patent. Patented Aug. 29, 1922.

Application filed May 13, 1921. Serial No. 469,087.

To all whom it may concern:

Be it known that I, JOACHIM TORRES-GARCIA, a citizen of the Republic of Uruguay, residing at New York, N. Y., United States of America, have invented new and useful Improvements in Traveling Toys, of which the following is a specification.

This invention relates to improvements in traveling toys, the object of the invention being to provide an improved device which may be applied to hobby horses, teeters and similar toys by means of which, in addition to the usual rocking motion, they are caused to progress in one direction, and which device is extremely simple in construction, inexpensive to manufacture and highly efficient in operation.

With the foregoing and other objects in view, which will appear as the description proceeds, the invention consists in the novel features of construction and combination of parts which will be more fully described hereinafter and particularly pointed out in the claims.

25 In the drawings accompanying and forming part of this specification,

Figure 1 is a perspective view of one form of toy embodying the present invention; and Figure 2 is a side elevation thereof, on 30 a smaller scale.

The same characters of reference designate the same parts in the different figures of the drawings.

In the form illustrated in the drawings, 35 the invention is applied to a supporting frame 2 provided with a seat 3 and legs 4, to the lower ends of which are secured a pair of rockers 5. The particular form of support is, of course, immaterial, and it will readily be understood that any suitable body may be substituted for the frame herein illustrated, to suit the fancy of the purchaser, without in the least affecting the spirit and scope of the invention.

45 In the present instance, the supporting body or frame is provided with a pair of perforated lugs or ears 6, between which is pivoted a depending member or lever 7 carrying at its lower end a transverse floor-engaging member 8. As shown in the drawings, each of the rockers 5 is provided approximately midway of its length with a recess 9 opening towards the floor, and the ends of the member 8 extend into said recesses, the vertical walls of which serve to

limit the swinging movement of the lever 7 on its pivot.

The feature of the present invention which I regard as of the greatest importance is that the length of the lever must be such that the distance between the pivotal point of the lever 7 and the floor-engaging surface of the member 8 is slightly greater than the vertical distance from said pivotal point to the floor.

The operation of the device is as follows, starting from the position shown in Fig. 2. Upon rocking forward, the weight of the operator is first transferred from the rear portions of the rockers to the member 8 and then to the front portions of the rockers. As soon as the center of gravity has been thrown sufficiently far forward, the lever 7 swings on its pivot until the ends of the floor-engaging member come into contact 75 with the front walls of the recesses 9 in the rockers. Upon reversing the rocking motion, the rear portion of the member 8 immediately engages the floor, thereby preventing swinging of the lever 7, while the 80 continued backward rocking brings the rear walls of the recesses 9 into engagement with the rear side of the member 8, as shown in Fig. 2, about the same time that the rear portions of the rockers engage the floor.

85 The action of the lever above described is facilitated by forming the member 8 somewhat wedge-shaped in cross-section, so that when in the starting position shown in Fig. 2, the lower front portion of said member is 90 somewhat above the floor, thus enabling it to swing freely as soon as the weight is transferred to the front portions of the rockers, and, on the other hand, just as soon as the rocking action is reversed the rear 95 portion of the member 8 engages the floor and receives the weight, thereby preventing the free swinging of the lever and causing it to throw the device bodily forward just prior to engagement of the floor by the rear 100 portions of the rockers. It will thus be seen that the action of the lever 7 is a combination pendulum-lever action.

I am aware that numerous devices have been proposed for producing a forward propulsion of a toy similar to that described, but many of these structures comprise complicated mechanisms, while others employ springs and similar devices. The present invention, however, is extremely simple as 110

compared with any of those devices, there being no springs or other mechanism whatever to get out of order.

While I have described in detail the structure herein illustrated, it is to be understood that I do not thereby limit my invention to the precise features of construction shown, as I am aware that many mechanical changes and modifications may be made 10 therein without departing from the spirit and scope of the invention as set forth in the claims appended hereto.

Having thus described my invention, what I claim is:

- 15 1. A traveling toy, comprising a body provided with rockers, a depending member pivoted to said body between said rockers, and normally occupying a position at one side of its pivotal point, the member being adapted to swing to the opposite side of said pivotal point when the body is rocked in one direction, and means carried by the depending member and adapted to engage the rock-
- 20

ers for limiting said swinging movement, said means being also adapted to engage the 25 floor on the reversal of the rocking movement of the body.

2. A traveling toy, comprising a body provided with rockers, each having midway of its length a recess opening toward the floor, 30 a depending lever pivoted to said body between said rockers, and a transverse floor-engaging member carried by said lever and having its ends projecting into said recesses, said lever normally occupying a position at 35 one side of its pivotal point and adapted to swing to the opposite side of said pivotal point when the body is rocked in one direction, said floor-engaging member being wedge-shaped in cross section, thereby to 40 engage the floor when the body is rocked in the opposite direction.

In testimony whereof I have signed my name to this specification.

JOACHIM TORRES-GARCIA.
